US00D534405S

(12) **United States Design Patent** (10) Patent No.: US D534,405 S
Concari (45) Date of Patent: ** Jan. 2, 2007

(54) CORDLESS DRILL

(75) Inventor: **Gabriel E. Concari**, Eldersburg, MD
(US)

(73) Assignee: **Black & Decker Inc.**, Newark, DE
(US)

(**) Term: 14 Years

(21) Appl. No.: **29/260,034**

(22) Filed: **May 18, 2006**

(51) LOC (8) Cl. 08-01

(52) U.S. Cl. D8/68

(58) **Field of Classification Search** D8/14.1,

(57) **CLAIM**

The ornamental design for a cordless drill, as shown and described.

DESCRIPTION

FIG. 1 is a left/front perspective view of a cordless drill

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.
